US00D976589S

(12) **United States Design Patent** (10) **Patent No.:** **US D976,589 S**
(45) **Date of Patent:** **** Jan. 31, 2023**

(54) **LUGGAGE**

- (71) Applicant: **JRSK, Inc.**, New York, NY (US)
(72) Inventors: **Stephanie Korey**, New York, NY (US);
Jennifer Rubio, New York, NY (US);
Bret Recor, New York, NY (US);
Charles Weber, New York, NY (US);
Seth Murray, New York, NY (US);
Ahyoung Park, New York, NY (US)
(73) Assignee: **JRSK, Inc.**, New York, NY (US)
(**) Term: **15 Years**
(21) Appl. No.: **29/697,883**
(22) Filed: **Jul. 11, 2019**

Related U.S. Application Data

- (63) Continuation of application No. 29/609,837, filed on Jul. 6, 2017, now Pat. No. Des. 877,507, which is a continuation of application No. 14/935,335, filed on Nov. 6, 2015, now Pat. No. 10,219,599.

(57) **CLAIM**

The ornamental design for luggage, as shown and described.

DESCRIPTION

FIG. 1 is a rear perspective view of a piece of luggage showing our new, original and ornamental design embodied therein, in accordance with the present invention;

FIG. 2 is a front perspective view of the piece of luggage of FIG. 1;

FIG. 3 is an elevated front view of the piece of luggage of FIG. 1;

FIG. 4 is an elevated rear perspective view of the piece of luggage of FIG. 1; and,

FIG. 5 is a bottom view of the piece of luggage of FIG. 1. Any dash-dash broken lines in the drawings represent unclaimed portions of the piece of luggage and form no part of the claimed design.

1 Claim, 5 Drawing Sheets
